DEFENSIVE PUBLICATION

UNITED STATES PATENT AND TRADEMARK OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

27 Sheets Drawing, 187 Pages of Specification

An electrical method for generating and maintaining an electrical directory entity in a data processing machine. The directory may be used to automatically locate objects in the computer system, e.g. in main store or on I/O devices. The objects are represented by electrical identifier signals received as input to the method. Electrical signals are generated comprising connected inner vertices and sinks. The signals comprising each inner vertex from a bit-index field, a flag field, and a connecting edge field. The inner vertices are connected in ascending order along a path in the tree structure by the electrical signals forming the edge fields of the inner vertices in the connected paths. The physical configurations of the electrical identifier signals are used as search arguments for insertions or deletion in a connected path when it is traced. The physical layout of the vertices permits total flexibility by allowing each next vertex in a connected path to be physically located anywhere in the directory entity. Each vertex other than the source is located in one of a pair of cells. Each edge field connects its vertex to two other vertices in a pair of cells. The edge fields may be in absolute, offset, or invertible form, each form having different advantages when using the invention, e.g. the invertible edge permits backward tracing along a connected path.
